STRUCTURAL UNIT

George F. Dalton, II, Cleveland Heights, Ohio

Application October 21, 1943, Serial No. 507,116

4 Claims. (Cl. 20—91)

This invention relates as indicated to structural units and more especially to a prefabricated unit so constructed and arranged that a plurality of such units may be conveniently combined to build up a continuous structure having a wide range of utility.

It is a principal object of my invention to provide a unit of the character described which utilizes to the fullest possible extent the strength of the components of which it is constructed.

It is a further object of my invention to provide a unit which may be fabricated either of metal, wood or synthetic materials and which is of great strength and rigidity while employing only a minimum weight of such material.

It is a further and more specific object of my invention to provide a structure of the character described which may be used either singly or in multiple and when a plurality of such units is combined, it may be assembled or disassembled with a minimum of effort while at the same time providing an extremely rigid and strong structure.

Other objects of my invention will appear as the description proceeds.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a broken plan view showing one embodiment of the principles of my invention; Fig. 2 is a transverse sectional view of a portion of the structure illustrated in Fig. 1 taken on a plane substantially indicated by the line 2—2; Fig. 3 is an enlarged sectional view of a portion of the structure illustrated in Fig. 2; Fig. 4 is a perspective view of one corner of a unit constructed in accordance with my invention; Fig. 5 is a perspective view of a key or locking bar which may be employed for the purpose of maintaining in assembled relation a plurality of units such as those illustrated in the previous figures; and Fig. 6 is a force diagram of a small section x of the structure illustrated in Fig. 3.

Referring now more particularly to Figs. 1 to 3, the building unit comprising my invention and which as previously indicated may be used either singly or in multiple in the construction of walls,

floorings, shorings or the large variety of types of structures which will be apparent to those familiar with the art, consists in its preferred embodiment of spaced plates 1 and 2 arranged in substantially parallel relation. These plates are maintained in assembled and spaced relation by means of a plurality of ribs or spacer members 3 preferably arranged at right angles to the plates 1 and 2. The spacer members 3 which extend in the same direction are preferably parallel with respect to each other and at right angles to such spacer members as extend transversely.

In the corners where the various components of the assembly abut, I have provided fillets such as 4 which may be of any conventional cross-section such as a quarter round triangle, rectangle, etc.

At the margins of the unit as thus constructed, the plates extend slightly beyond the spacer members and on each of such marginal portions there is provided a longitudinally extending member 5 with each pair of such members provided with an undercurrent recess forming one component of a male and female connection by which a plurality of the units may be combined into a composite structure. As a convenient means of thus assembling and interlocking a plurality of these units, I have provided a key or locking bar 6 which has grooves 7 on opposite faces thereof complementary to the slope of the faces of the elements 5 so as to securely interlock therewith as the key member 6 is inserted longitudinally into the locking slot along the edge of the structure. The grooves provided by means of the members 5 as well as the grooves 1 in the key member 6 may be tapered either transversely or longitudinally or both, depending upon the particular use to which the ultimate structure is to be placed.

The bar 6 is merely illustrative of the many forms of interlocking bars which may be used. Any of the wide variety of available tenon or tongue and groove combinations may be employed. The particular form selected for use will be determined by the particular use for which the ultimate assembly is designed.

As previously indicated, the various parts which comprise one unit, i. e. the plates 1 and 2, the spacers 3, the fillets 4, and the members 5, may all be formed of the same or different materials depending again upon considerations of economy and the desired use for which the unit is made. In the preferred embodiments of my invention however, the elements 1, 2 and 3 are all made of

plywood being built up of such a number of different sheets as to provide the strength required. It is an essential feature of my invention that all of the parts thus assembled united by means of an atomic bond. By the use of the term "atomic bond" as employed in this specification and throughout the appended claims, I intend to include either a weld or similar bond in case the elements are made of metal, and a glued or similarly cemented joint in case the elements are made of wood or other non-metallic material. The employment of an atomic bond throughout the entire assembly for the purpose of joining the various parts is, as indicated, a very important factor since the prevention of all relative movement between the various parts of the assembly is one of the principal factors responsible for the extremely high and unexpected strength and rigidity of the structure as thus made. In practical tests on structures made in accordance with the foregoing description, it has been demonstrated that the parts will carry many times the load which materials such as plywood would ordinarily be expected to carry. By the atomic bonding of the entire assembly preventing any relative movement between its component parts, any applied load will be resolved into either a vertical or horizontal shear, the type of stress to which materials like plywood are best capable of withstanding.

It is further and important factor that the normal plane of the spacer members 3 is at substantially right angles to the normal plane of the sheets or plates 1 and 2.

By the use of the term "normal plane" as used herein and throughout the appended claims, I intend to indicate the plane of the element in question which is determined by the direction of grain structure in such element. Thus, in a composite plywood plate the "normal plane" thereof is generally parallel to the flat surface of such plate. Arranging the various elements of the assembly with the normal planes thereof either parallel or at right angles to each other in conjunction with the atomic bond previously referred to, produces a structure of unexpectedly great strength and rigidity.

In elements 3 which act as the web members of the structural unit or panel in Fig. 1, spanning between lines of support 8, horizontal and vertical shearing forces exist when the panel is loaded. These vertical and horizontal shearing forces are greatest at the supports 8 and a maximum along the lines of the neutral axis 13 of the web member 3, Figure 3.

Fig. 6 represents a small unit area x removed from web 3. The vertical shearing forces 9 are equal and opposite. Likewise the horizontal shearing forces 10 are equal and opposite. The resultant force 11 between vertical force 9 and horizontal force 10 is a diagonal tensile force. By the same reasoning the resultant force 12 is a diagonal compressive force. Diagonal tensile force 11 would have the tendency to pull or disrupt any web material 3.

By using a fillet element 4 atomically bonded to elements 1-3 and 2-3 the horizontal forces 10 can be properly transmitted into covers 1 and 2. However, elements 4 may be eliminated when the connection or bond between elements 1 and 3; and 2 and 3 is sufficient to develop the desired strength of panel.

It is a known proven fact that the shearing strength of some materials such as wood across the grain is far greater than with the grain, and

that the tensile and compressive strength with the grain is far greater than across the grain. Being aware of the above facts I have conceived the idea of utilizing materials having great shearing tensile and compressive strength in all directions. Plywood is such a material.

Development of stresses, as indicated above, in my unit has been borne out by actual laboratory tests on panels showing enormous strength and development of the full strength of the material.

The unit comprising my invention may be employed as indicated either singly or in multiple and may be used in either permanent or temporary structures wherever it is desired to provide a wall or beam capable of carrying great loads. One particularly desirable use of the unit of my invention is in building up shorings or forms in concrete construction whether the surface of the green concrete to be supported is vertical or horizontal. Not only may the various units be quickly and easily joined together by means of a key member such as 6, but after the shoring or form work is to be removed they may be as easily and quickly disassembled without damage to the individual units so that they may be used over many times.

The foregoing is an indication of only a few of the advantages and uses of my construction and is only a partial explanation of the reasons for the great strength and rigidity of the unit which has been described. Further uses and advantages will be apparent to those skilled in the art and a fuller understanding of the reasons for such great strength and rigidity may be appreciated from a more detailed study in which the manner of the stresses are distributed and carried may be developed in greater detail, a study which however is believed not necessary in the present description of the basic principles of my invention.

Other modes of applying the principle of the invention may be employed, change being made as regards the details described, provided the features stated in any of the following claims or the equivalent of such be employed.

I therefore particularly point out and distinctly claim as my invention:

1. A structural unit comprising spaced substantially parallel relatively thin sheets, thin spacer members extending transversely between said sheets, said spacer members being positioned inwardly of and adjacent to and extending along the transverse edges of said sheets, fillet members in the corners between the interior surfaces of said sheets and the interior surfaces of said spacer members, elongated, substantially flat locking members positioned in the corners between the interior surfaces of sheets and the exterior surfaces of said spacer members, the elongated locking members and fillet members being coextensive on opposite sides of the spacer members, said sheets, spacer members, fillet members and locking members being of wood and being atomically bonded at their surfaces of contact, each of said locking members having an angular surface that forms an undercut recess in conjunction with an exterior surface of a spacer member.

2. A structural unit as defined in claim 1 wherein said sheets and spacer members are formed of plywood.

3. A structural unit as defined in claim 1 wherein said locking members are spaced inwardly from said transverse edges of the sheets.

4. A wall comprising a number of structural units as defined in claim 1, said units being joined together by locking bars, each of said locking bars having two plane parallel sides abutting parallel portions of said spacer members on two adjacent structural units, said bar also having oppositely disposed V shaped surfaces, which connect said parallel surfaces, one of said V shaped surfaces

engaging an undercut recess on one unit and an undercut recess on an adjacent unit and the other of said V shaped surfaces engaging two other undercut recesses on the same adjacent structural units, whereby the transverse edges of adjacent structural units are drawn into tight abutting relationship.

GEORGE F. DALTON, II.
